(57) **CLAIM**

The ornamental design for an automotive center console, as shown and described.

DESCRIPTION

FIG. 1 is a top, front, left side perspective view of an automotive center console showing my new design;

FIG. 2 is a bottom, rear, right side perspective view thereof;

FIG. 3 is a front view thereof;

FIG. 4 is a back view thereof;

FIG. 5 is a left side view thereof;

FIG. 6 is a right side view thereof;

FIG. 7 is a top view thereof;

FIG. 8 is a bottom view thereof; and,

FIG. 9 is an enlarged view of the selected portion 9 in FIG. 8.

The dash-dash broken lines shown in the drawings depict portions of the automotive center console that form no part of the claimed design. The dot-dash broken lines, in FIGS. 8 and 9, represent the boundary of the enlarged portions, of the automotive center console and form no part of the claimed design.
